UNITED STATES PATENT OFFICE.

JOSEPH M. SECHE, OF PHILADELPHIA, PENNSYLVANIA.

ELECTRIC IRON.

1,419,173.

Specification of Letters Patent. Patented June 13, 1922.

Application filed January 24, 1922. Serial No. 531,328.

To all whom it may concern:

Be it known that I, JOSEPH M. SECHE, a citizen of the United States, residing at Philadelphia, in the county of Philadelphia and State of Pennsylvania, have invented a new and useful Improvement in Electric Irons, of which the following is a specification.

The principal object of the present invention is to avoid the fire hazard heretofore incident to the use of electric irons; another object of the invention is to provide an electric iron which is fool proof in the sense that no matter how carelessly or negligently it is handled or how it is put down or thrown down it will not ignite or set fire to anything; another object of the invention is to protect the line wire plug; and another object of the invention is to provide a device or attachment capable of application to existing electric irons and adapted to impart to them the desirable features above set forth.

The invention, generally stated, comprises an electric iron provided with two normally open circuit makers of which one is operative in the plane of the iron and is adapted to close under the weight of the up-ended iron to heat it and of which the other is operative perpendicularly to the plane of the iron to lift the heel of the iron and is adapted to close under pressure applied manually to the iron for ironing.

The invention also comprises the improvements to be presently described and finally claimed.

A description will now be given of the embodiment of the invention chosen from among other embodiments for illustration in the accompanying drawings forming part hereof and in which—

Figure 1 is a side view of an electric iron embodying features of the invention and with parts of the housing broken away.

Fig. 2 is a top or plan view with parts in section.

Fig. 3 is a view, partly in section, showing the iron in up-ended position.

Fig. 4 is a view taken generally on the line 4—4 of Figure 1 looking toward the right.

Fig. 5 is a view taken on the line 5—5 of Figure 1.

Fig. 6 is a view taken on the line 6—6 of Figure 1, and

Fig. 7 is a diagrammatic view illustrative of the circuit connections.

In the drawings 1 is an electric iron. 2 is a terminal block in fixed relation to the heel of the iron and spaced from or above the face of the iron. 3 are brackets supporting the block in the described position and the brackets are shown as projecting from a plate 4 detachably applied to the rear of the iron as by means of screws and with a heat insulating pad between the iron and the plate. There are terminal contacts carried by the block 2 and of them one pair 5 is operatively arranged toward the face of the iron and the other pair 6 is operatively arranged away from the rear of the iron. Circuit connections 7 extend from the iron to the described contacts, there being one conductor to one contact of each pair of contacts. The contacts are of course insulated from each other as shown by the block 2 which is of insulating material. 8 is a movable terminal block arranged at the heel of the iron and in the space provided by the described arrangement of the fixed terminal block 2. There are terminal contacts carried by the movable terminal block 8 and one pair of these contacts 9 is operatively arranged at the top of the block opposite the contacts 5, and the other pair of these contacts 10 is operatively arranged at the rear of the block. There are circuit connections 11 for the contacts of the movable terminal block 8, and they include pins 12 accessible through an opening in the block 2 and adapted to co-operate with a line plug not shown.

13, Fig. 4, are guides for affording the movable terminal block 8 a range of motion in respect to the fixed terminal block 2 and beyond the plane of the face of the iron. 14 are projections or eyes extending from the bracket 4 and co-operating with a pair of guides 13. The other pair of the guides 13 work through openings in the block 2. 15 are springs for normally holding the movable terminal block 8 beyond the face of the iron and away from the fixed terminal block 2 and in position to break the path of the circuit at the contacts 5 and 9. 16 is a movable contact block confronting both terminal blocks 2 and 8. 17 are current carrying bridges on the contact block 16, and they serve to make and break circuit at the contacts 6 and 10. 18

are guides for the movable contact block and they permit or afford it a range of movement toward and away from the blocks 2 and 8. 19 are springs for normally 5 pressing the contact block 16 away from the terminal blocks 2 and 8 in order to break circuit at the contacts 6 and 10. There is a sectional housing and it is shown as consisting of two parts of which the part 20 10 is secured to the movable terminal block 8 and extends downward as at 21. The other part of the housing 22 is secured to the contact block 16 and the two parts of the housing are movable in respect to each 15 other so that the housing projects and conceals the described mechanism without interfering with the movement of the parts.

The normal position of the parts is such that the path for the current is interrupted 20 at all the contacts and the portion 8^a of the block 8 is projected in all positions of the iron except two. This condition of affairs obtains so that in all positions of the iron except two the circuit is interrupted. Furthermore if the iron is hot from previous 25 heating the spring pressed block 8 operates to lift its heel, as shown in Figure 1, so that the iron rests on its toe and air has access to its face and the result is that while the toe 30 may scorch a little it will not ignite the material, even fabric upon which it rests, and this is true although the iron had been previously heated to a very high heat, it being of course understood that since no current 35 may reach the iron, it gradually cools off without danger of setting fire to anything. To heat the iron it is up-ended, as shown in Fig. 3, with the result that there is established a path for current by way of 12, 11, 40 10, 17, 6 and 7. If the iron should be knocked over it assumes the safe position shown in Figure 1 with the current off and the heel raised, or some other safe position with the current off or the iron raised. When the 45 iron has become sufficiently hot it is used in the ordinary manner and the manual pressure on the iron brings its face and the face of the part 8^a in substantially the same plane, thus shifting the block 8 toward the 50 block 2 and closing the circuit at the contacts 5 and 9, so that the current heats the iron when in use. If the ironer releases the iron from pressure, the springs 15, acting on the part 8 and block 8, raise the heel of 55 the iron, thus not only interrupting the circuit but also providing for such access of air under the face of the iron as prevents the ignition of the fabric or other object upon which the nose of the iron and the part 60 8^a rest. It may be remarked that the pins 12 are remote from the iron and in fact are sheltered by the block 2, so that the contacts in the plug as well as the pins are protected from heat and therefore are durable.

65 The projection portion 23 on the movable

contact block 16 (Figs. 1 and 2) when the iron is up-ended, comes between the fixed and movable terminal blocks and separates them.

It will be obvious to those skilled in the art to which the invention relates that modifications may be made in details of construction and arrangement without departing from the spirit of the invention which is not limited as to those matters or otherwise than 75 as the prior art and the appended claims may require.

I claim:

1. An electric iron provided with two normally open circuit breakers of which one is 80 operative in the plane of the iron and is adapted to close under the weight of the up-ended iron to heat it and of which the other is operative substantially perpendicular to the plane of the iron to lift the heel 85 of the latter and is adapted to close under pressure applied to the iron for ironing.

2. An electric iron having in combination two normally open circuit breakers of which one is operative in the plane of the iron and 90 is adapted to close under the weight of the up-ended iron to heat it and of which the other is operative substantially perpendicular to the plane of the iron to lift the heel of the latter and is adapted to close under pressure applied to the iron for ironing, and 95 a sectional housing enclosing the said members and adapted to permit of the described movements thereof.

3. An electric iron having in combination 100 circuit connections, a circuit closer arranged at the heel of the iron and operative in two directions to close the circuit, and spring means adapted to press said circuit closer into circuit breaking position and into position for raising the heel of the iron and adapted to yield when the iron is up-ended and is pressed down for ironing.

4. An electric iron having in combination 110 circuit connections, a fixed terminal block arranged at the heel of the iron and having angularly disposed contacts, a movable terminal block adapted for projection beyond the face of the iron and having angularly disposed contacts, a movable contact block 115 co-operating with said terminal blocks and having bridge contacts, and guides and springs for said movable blocks, substantially as described.

5. An attachment for electric irons comprising the combination of a plate having brackets and guides and adapted for attachment to an electric iron, a fixed terminal block carried by the brackets and provided with angularly disposed contacts, a movable 125 terminal block provided with angularly disposed contacts and adapted to project beyond the face of the iron, guides on the movable block co-operating with the guides on the plate, springs and limit guides between 130

the fixed and movable blocks, a movable contact block having bridges, and springs and limit guides interposed between the contact block and one of the terminal blocks, substantially as described.

6. In an electric iron the combination of three elements arranged at the heel of the iron and of which one is a fixed terminal block and of which the other two are movable in respect to the first in directions at substantially right angles to each other and 5 are respectively a movable terminal block and a contact block, springs normally separating said blocks, and circuit terminals from the iron and from the line provided on the fixed and movable terminal blocks respectively and adapted for contact with each other and with bridge contacts provided on the contact block.

10 7. In an electric iron the combination of

three elements arranged at the heel of the iron and of which one is a fixed terminal block and of which the other two are movable in respect to the first in directions at substantially right angles to each other and 25 are respectively a movable terminal block and a contact block, springs normally separating said blocks, and circuit terminals from the iron and from the line provided on the fixed and movable terminal blocks respectively and adapted for contact with each other and with bridge contacts provided on the contact block there being an opening in the fixed terminal block for the accommodation of a line plug.

15 8. An electric iron provided with a movable element arranged at its heel, and spring means for causing said element to normally raise the heel of the iron.

30 35 JOSEPH M. SECHE.
